UNITED STATES PATENT OFFICE.

EUGENE H. TAYLOR, OF LYNN, MASSACHUSETTS.

BEATING-OUT MACHINE.

SPECIFICATION forming part of Letters Patent No. 562,865, dated June 30, 1896.

Application filed October 8, 1895. Serial No. 565,039. (No model.)

To all whom it may concern.

Be it known that I, EUGENE H. TAYLOR, a citizen of the United States, residing at Lynn, in the county of Essex and State of Massachusetts, have invented certain new and useful Improvements in Beating-Out Machines, of which the following is a specification.

My invention relates to machines for beating out the soles of boots and shoes, and I have represented it herein as applied to the machine shown in Letters Patent No. 384,893, issued January 19, 1888, to J. C. Cutcheon.

By means of my improvement I do away with the necessity of moving the slide which carries the shoe-supporting jack to the front of the machine and back again by hand, as shown in the machine referred to. I accomplish this result by causing the slide to be automatically thrown out to the front of the machine into position for the removal of the shoe after it has been released from pressure, and to be also thrown back again under the mold after another shoe has been placed upon the jack and the machine has again been started.

The Cutcheon machine above referred to is duplex, that is, it is provided with two molds, two jacks, and a common mechanism for operating the same simultaneously, so that when one shoe is under pressure the other one is in a position to be removed from its jack and to be replaced by another. Inasmuch, however, as my automatic mechanism, when placed upon a duplex machine, may be applied in precisely the same manner to each half of the machine, so as to operate each jack independently of the other, I have not thought it necessary to show both halves of the complete duplex machine, but have illustrated in the accompanying drawings one-half of a machine built substantially in accordance with the Cutcheon patent, showing also my automatic throw-out applied thereto.

In said drawings, Figure 1 is a side elevation of a beating-out machine with some parts of the mechanism omitted and broken away in order to better illustrate my improvements. Fig. 2 is a section taken on line $x-x$ of Fig. 1, looking from the rear of the machine. Fig. 3 is a horizontal section taken just above the jack-carrying slide and looking downward.

Fig. 4 is a horizontal section taken on the line $y-y$, in Fig. 1.

The parts of the mechanism which move the jack up and down beneath the mold are lettered to correspond with the same parts, as shown in the Cutcheon patent, A being the framework of the machine, F the table which carries the jack-supporting slide, H the jack-supporting slide, H' the jack, and I the mold. The table F is provided with slides c', which move up and down upon the guides D. The table is moved up and down by means of a toggle mechanism consisting of the toggle-link M, pivoted at its upper end to the table and at its lower end to the toggle-link N, which latter is pivoted to the framework of the machine, and also to a link N', the lower end of which is provided with a box h, which embraces the crank k of the shaft O. This shaft is provided upon its outer end with a gear O', which meshes with the pinion O' upon the driving-shaft P. Said driving-shaft is provided with a friction-wheel, driving-pulley, and brake-shoe, and a treadle Q', and cams operated thereby are used to start and stop the machine, all substantially as shown and described in the Cutcheon patent, to which reference is made for a fuller understanding of these parts, they forming no part of the present invention.

To the machine as thus constructed I add a vertical shaft 10, mounted near its lower end in a journal-box 11, pivoted to a cross-tie 12, secured to the framework of the machine. At its upper end the shaft 10 turns in a box 13, secured to the table F, and a pinion 14 is mounted on said shaft, being splined thereto, as shown at 16, whereby it may be made to slide up and down thereon by being confined between the box 13 and a plate 15, bolted to the top of the table F. Thus while the pinion is allowed to slide up and down on the shaft, it is prevented from turning independently thereon. The jack-supporting slide H is provided with a rack, as shown, which meshes on the pinion 14.

The shaft 10 is provided at its lower end with a second pinion 17, which meshes with the teeth formed on a segment 18, which segment is pivoted at 19 to a guide 20, corresponding in its general outlines and dimen-

sions with the segment which slides across the face thereof. This guide 20 is bolted to the framework of the machine, or it may be cast integral therewith. The segment 18 is provided on that face which is opposite to the guide 20 with a projection 21, which slides in a groove 22, formed in the cam 23, the said cam being rigidly secured to the shaft O.

The parts are so adjusted that when the table F and its jack are in their highest position, as shown at Figs. 1 and 2, that is, with the shoe pressed against the mold, the segment 18 has reached the limit of its forward movement and the jack-supporting slide H has thereby been carried back into the proper position directly under the mold. When now, the operator starts the machine by depressing the treadle, the shaft O revolves and with it the cam 23. The segment 18 is thereby moved backward, the shaft 10 is caused to revolve in the direction of the arrow shown in Fig. 1, and the jack-supporting slide is thrown forward to the front of the machine. The machine now stops and the jack remains in the proper position for the removal and replacing of the shoe until the machine is again started.

In order to insure the proper clearance of the jack from the mold, the groove in the cam is so shaped that the shaft 10 does not revolve until after the jack has moved away from the mold a sufficient distance. By my automatic mechanism as thus constructed, I not only secure the moving backward and forward of the jack-supporting slide H without any intervention or effort on the part of the operator, but I also provide against the accidental displacement of the jack from its

proper position when it is being pushed up by the toggle mechanism against the mold. 40

While I have shown and described my improvement only as applied to a duplex machine, it is obvious that it is equally applicable to a non-duplex machine, or to a single-section machine, both well known in the art. 45

I claim as my invention—

1. In a beating-out machine, an automatic throw-out for the jack or last, comprising a jack-carrying table, a jack-supporting slide thereon, a shaft, a pinion splined thereto and arranged to move up and down with the jack-carrying table, a rack upon the jack-supporting slide, meshing with said pinion, and means for automatically rotating said shaft during the proper period of vertical motion of the jack-carrying table, all substantially as described. 50

2. In a beating-out machine of the character described, an automatic throw-out for the jack-supporting slide, comprising a jack-carrying table, a jack-supporting slide thereon, a shaft, a pinion splined thereto and arranged to move up and down with the jack-carrying table, a rack upon the said slide which meshes with said pinion, a cam secured to the driving-shaft of the machine, and means operated by said cam for automatically rotating the shaft, all substantially as described. 60

In testimony whereof I have hereunto subscribed my name this 28th day of September, 70 1895.

EUGENE H. TAYLOR.
